ELECTRICAL APPARATUS

Theodore C. Riebe, Chicago, Ill., assignor to
Automatic Electric Laboratories, Inc., Chicago,
Ill., a corporation of Delaware

Application October 18, 1943, Serial No. 506,685

8 Claims. (Cl. 250—33)

The present invention relates to electrical apparatus provided with separable electric connections and, more particularly, to such connections for interconnecting a supporting structure or apparatus with a readily removable or demountable structure or apparatus.

It frequently occurs that units of electrical apparatus must be demounted or removed to facilitate portability or the repair of the apparatus. Where it is desired to provide for easy and rapid disassembly of apparatus it is particularly desirable to provide separable electrical connections which do not require the performance of any additional operations and which, however, will be positive in operation, which will provide a self-cleaning wiping contact, and which will provide a relatively high degree of contact pressure. One such instance which required separable contacts having the above characteristics occurred in a portable direction finder having a pair of spaced loop antennas. In accordance with the present invention each loop antenna and its supporting arm was readily removable and the electrical connections between the arm and the supporting structure were made by sets of contacts. One of these sets of contacts was resilient and the cooperating contact was rigid. The contacts were so positioned relative to each other and to a separable hinge connection that one set of contacts was provided with a sufficient moment arm as to cause displacement of the resilient contacts and to produce between the sets of contacts a predetermined degree of contact pressure.

It therefore is an object of the present invention to provide, in electrical apparatus, an improved separable contact structure.

It is another object of the present invention to provide for a demountably supported unit of electrical equipment an electrical contact means so related to the separable supporting means for the apparatus as to produce positive contact connection with a predetermined pressure when the unit is in assembled position.

The invention is set forth with particularity in the appended claims. Other and further objects of the invention will subsequently become apparent by reference to the following description taken in connection with the accompanying drawings wherein Figure 1 shows the apparatus to which the present invention has been applied; Fig. 2 is a side view, partially in section, of the apparatus shown in Fig. 1; Fig. 3 is a top view of the supporting structure and one set of the separable electrical contacts; and Figs. 4 and 5 show the manner in which the contact structure of Fig. 3

cooperates with the contact structure of the demountable or removable electrical apparatus unit.

Referring more particularly to Figs. 1 and 2, there is shown a portion of a radio receiving cabinet 11, above which there is provided a handwheel 12 attached to a supporting structure by means of which a plurality of spaced loop antennas may be rotated. The antenna structure cooperating with the receiver 11 consists of a pair of spaced parallel loop antennas, one of which 13 is seen to the left in Fig. 1, and the other of which 14 is seen to the right in Fig. 2. Intermediate the two outer spaced parallel loop antennas, such as 13 and 14, there is provided a sense antenna 15. The handwheel 12 is arranged to rotate a supporting column or shaft 16 which is provided with a supporting assembly 17 arranged to demountably support two loop antenna supporting arms 18 and 19 associated respectively with the outer loop antennas 13 and 14.

Each of the loop antennas is supported adjacent the outer extremity of each supporting arm by an apparatus which includes a positioning pin 21 secured to a plate 22 which is fastened by means of screws 23 to the upper surface of one of the arms, such as the arm 19. The centering pin 21 is arranged to project through a slot in an adjustable plate 24 secured to the bent arm support 25. The slotted plate 24 is pivoted by a fastening screw 26 and is secured in proper angular position by a set screw 27 operating in conjunction with an arcuate slot 28 in the horizontal portion of the arm 25. The arm 25 at its upper extremity is connected to a supporting column 29 positioned immediately adjacent the underside of the loop antenna 14. Beneath the supporting structure 29 there is provided a knurled operating member 31 which engages a threaded portion, not shown, which forms an extension of a connector housing 32 mounted on the outer extremity of arm 19. Within the threaded portion of the housing 32 there is provided one portion of a male and female connector plug, the other portion being contained within the supporting structure 29 associated with the loop antenna. The adjustment provided by the slotted plate 24 and the arcuate aperture 28 of the arm 25 permits the loop antenna 14 to be oriented so that it is effectively parallel to the other cooperating spaced loop antenna, such as the antenna 13.

The antenna 15 is supported from a column or cylindrical member 33 which extends on downwardly to suitable connections within the main supporting column 16. The column 33 is provided with a collar 34 arranged to cover an aper-

ture in a rain shield or cover 35 which surrounds the connections to the loop antenna arm structures 18 and 19. The loop antenna 15 is secured in position by a pair of knurled thumb screws 36 and 37.

Referring now to Figs. 2 to 5, it will be seen that the inner extremities of the arms 18 and 19 are each retained in position by a separable hinge structure. The separable hinge structure includes two double hook members 38 and 39 secured to the upper plate of the assembly 17 by suitable fastening means, such as screws 41. Each of the members 38 and 39 is provided with two portions, as may be seen from Fig. 3, wherein the member 38 has hook portions 42 and 43. The supporting hook portions 38 and 39 are spaced apart on a circular member 17 so as to provide a space for the insertion of the arms 18 and 19 and also to provide room for the cooperating sets of contact members required to complete the electrical connections between the apparatus supported by the arms and the apparatus associated with the supporting column 16. The plate 17 has a central aperture 44 to receive the lower extremity of the rod which joins the supporting shaft 33 for the intermediate loop antenna 15. The plate 17 also has two other apertures 45 and 46 to register with portions of an insulating plate 47 on which there are mounted numerous resilient contacts such as 48, 49, 51 and 52. Each of these contacts is similar in construction to the arrangement shown in the cross-sectional portions of the insulating plate 47 in Figs. 4 and 5. Thus the resilient contact spring 49 is supported on an elongated flat metal member 50, and both the member 50 and the resilient contact spring member 49 are secured in position by a rivet 53. The intermediate portion of the spring contact 49 is arched above the contact plate 50, and the end of the resilient contact 49 bears against the contact plate 50 so that when the contact 49 is displaced the outer extremity will be moved longitudinally along the plate 50.

Each of the contacts 48, 49, 51 and 52 is arranged to cooperate with one of a plurality of rigid contacts, such as the contact 54 supported adjacent the extremity of the antenna arm 19. The contact 54 is, of course, suitably insulated from the arm 19 by being supported in a block of insulating material 60 retained in position by suitable fastening means, such as the screw 61. The upper end of the contact member 54 is provided with an annularly recessed portion 58 about which the end of a conductor might be secured, which conductor extends to the other extremity of the arm to the electrical contact interconnecting that end of the arm with the apparatus such as the loop antenna 14. Adjacent the inner extremity of the arm 19 there is provided a pair of pins, one of which 55 is shown in cross section in Figs. 4 and 5, and the other of which 56 is shown in Fig. 2. Similarly, the arm 18 is provided with two pins, only one of which 57 is visible in Fig. 2. The pins 55 and 56 of the arm 19 engage the right-hand portions of the upright members 38 and 39.

It will be noted from Fig. 4 that in order to insert these pins into the hook portions, such as the hook portion 43, the arm 19 must be raised in order to clear the forward portion 40 of the hook member 43. After the pin 55 is in engagement with the upper arcuate portion of the hook member 43, the arm may be lowered so that the lower side thereof will engage the upper surface of the plate 17 as is shown in Fig. 5. Thus the arm

is now in position and the contact 54 has wipingly engaged its cooperating contact 49 and has caused a displacement thereof. The contact 54 is located some distance from the pivotal axis of the pins 55 and 56 so as to have a certain moment arm. This moment arm insures a predetermined pressure between the contact 54 and the contact 49.

Thus it will be appreciated that the resilient contacts are arranged to be wipingly engaged by the cooperating contacts mounted on the arms 18 and 19 and the weight of the apparatus supported by these arms causes the contacts to be closed with a predetermined pressure. It furthermore will be appreciated that such an arrangement comprising a separable hinge connection interconnecting the support with the demountable or readily separable electrical units facilitates its rapid assembly and disassembly.

The arrangement shown comprising a separable hinge connection interconnecting electrical apparatus with a support has been applied to the antenna system of a radio direction finder. It will be understood, however, that a similar arrangement of a separable hinge connection and cooperating contacts may be provided for other electrical apparatus which is to be mounted on a support where it is desired to provide for the rapid assembly or disassembly of the equipment. Furthermore, such an arrangement will be of particular advantage where a unit of electrical equipment must frequently be removed for inspection or for repair and replacement.

While for the purposes of illustrating the present invention the invention has been shown as applied to a spaced loop antenna system of a radio direction finder, it is to be understood that I do not wish to be limited thereto since the principles employed and the apparatus embodying these principles are susceptible of similar applications in other electrical apparatus as may be commensurate with the scope of the appended claims.

What is claimed is:

1. In a portable directional antenna system the combination of a pair of spaced loop antennas each mounted adjacent the outer extremity of a supporting arm, a central supporting structure for said arms including a plurality of hook members spaced apart to permit the insertion therebetween of a portion of said loop antenna supporting arms, a hook engaging pin arranged on each side of said antenna arm for engagement with said hook portion, a plurality of resilient electrical contacts carried by said central supporting section, a plurality of electrical contacts located adjacent the inner end of each of said loop antenna supporting arms on the bottom side thereof, said contacts being so arranged that when said arms are being placed in engagement with said hook portions of said central supporting member the contacts of said arm will slidingly engage and displace the cooperating resilient contacts whereby a high degree of repressure will exist between said contacts.

2. In a portable directional antenna system, the combination of a plurality of spaced antennas, a like number of support members, each of said members supporting adjacent one end thereof of one of said antennas, contact means secured to the other end of each of said support members, a rotatable support, contact means secured to said rotatable support adapted to cooperate respectively with the said contact means of said antenna supporting member, a pair of hook mem-

bers for each of said antenna supporting members secured to said rotatable support, and means secured to each of said antenna supporting members at the ends thereof securing said contact means whereby said last-named means may be placed under said hook members when said antenna supporting member is held at an angle with respect to said rotatable support and whereby cooperation between said hook means and said last-named means controls both said contact means of said antenna supporting member and of said rotatable support to cooperate with a wiping action to complete an electrical connection therebetween as said antenna supporting means is moved to a horizontal position with respect to said rotatable support.

3. In a directional antenna system for a portable radio receiver, the combination of a central supporting structure including a plurality of hook members and a plurality of contact members, a plurality of antenna supporting arm members detachably secured to said central supporting structure, each of said arm members including a plurality of pin members and a plurality of contact members adjacent one end thereof, and a loop antenna secured to the other end of said arm members, said pins and said contact members of each of said arm members cooperating respectively with said central supporting structure hook and contact members to form diametrically opposite spaced antenna supporting arms electrically connected to said radio receiver through said contact members, said hook members cooperating respectively with said pin members to provide a hinge whereby said arm members may be readily detached as separate units from said central supporting structure to facilitate portability.

4. In an antenna system for a radio direction finder, the combination of a central supporting structure, a pair of diametrically opposite arm members supported by said structure, a loop antenna secured to one end of each of said arms, thereby providing a pair of loop antennas horizontally spaced apart a distance equal substantially to twice the length of one of said arm members, and means secured to the other end of each of said arm members and to said central supporting structure forming a detachable hinge member whereby said arm members may be readily removed from said central supporting structure by merely rotating the diametrically opposite ends of said arms upwardly from said horizontal position.

5. In an antenna system for a radio direction finder, the combination of a central supporting structure, a pair of diametrically opposite arm members supported by said structure, a loop antenna secured to one end of each of said arms, thereby providing a pair of loop antennas horizontally spaced apart a distance equal substantially to twice the length of one of said arm members, means secured to the other end of each of said arm members and to said central supporting structure forming a detachable hinge member whereby said arm members may be readily removed from said central supporting structure by merely rotating the diametrically opposite ends

of said arms upwardly from said horizontal position, and means also secured to the said other end of said arm members and to said central supporting structure forming detachable electrical contact means whereby the electrical circuits from said antennas to said radio direction finder may be automatically disconnected responsive to the removal of said arms from said central supporting structure.

10 6. In a radio direction finding system, the combination of a rotatable support, a readily demountable radio antenna supporting arm cooperating therewith, a separable hinge connection interconnecting said arm and said support, electrical contact means located adjacent said hinge connection and associated with said rotatable support and said supporting arm, said means including a resilient contact arranged to be wipingly engaged by a cooperating contact and to be displaced thereby when said arm is in cooperative relationship with said rotatable support thereby to complete an electrical circuit between said radio antenna and said direction finding system.

25 7. The combination comprising a central supporting structure, a demountable arm member including a loop antenna secured to one end thereof supported by said structure, a separable hinge interconnecting said structure and said arm including a pair of hooks and a pair of pins cooperating with said hooks to form a fulcrum about which said arm member may be pivoted, and sets of contacts carried by said structure and by said arm member for cooperation therebetween, one 30 of said sets of contacts being resiliently mounted so as to be displaced by the cooperating set of contacts when said demountable arm member is supported upon said supporting structure whereby the length of said arm from said fulcrum to 35 40 said antenna maintains a reliable electrical contact pressure between said sets of contacts.

8. The combination comprising a central supporting structure, a demountable arm member including an antenna secured to one end thereof supported by said structure, a separable hinge interconnecting said structure and said arm including a pair of hooks and a pair of pins cooperating with said hooks to form a fulcrum about which said arm member may be pivoted, said 45 hooks being mounted on said structure and said pins being mounted on said arm member, and sets of contacts carried by said structure and by said arm member for cooperation therebetween, one of said sets of contacts being resiliently mounted so as to be displaced by the cooperating set of contacts when said demountable arm member is supported upon said supporting structure whereby the length of said arm from said fulcrum to said antenna maintains a reliable electrical circuit 50 between said antenna and said supporting structure, said cooperating sets of electrical contacts being disconnected to open said circuit between said supporting structure and said antenna responsive to rotation of said antenna arm about 55 60 65 said fulcrum to remove said arm member from said central supporting structure.

THEODORE C. RIEBE.
